By Daniel Breed Atty.

UNITED STATES PATENT OFFICE.

MARTIN J. BUTZEL, OF BOULDER, COLORADO, ASSIGNOR TO LOUIS I. BUTZEL, OF SAUGERTIES, NEW YORK.

MUFFLE-FURNACE.

SPECIFICATION forming part of Letters Patent No. 246,939, dated September 13, 1881.

Application filed September 17, 1880. (No model.)

To all whom it may concern:

Be it known that I, MARTIN J. BUTZEL, a citizen of the United States, residing at Boulder city, in the county of Boulder and State of Colorado, have invented certain new and useful Improvements in Muffle-Furnaces; and I do hereby declare the following to be a full, clear, and exact description of the invention, such as will enable others skilled in the art to 5
10 which it appertains to make and use the same, reference being had to the accompanying drawing, and to letters or figures of reference marked thereon, which form a part of this specification.

The chief object of my invention is a convenient and practical apparatus for the purpose of condensing and saving fumes which carry off valuable metals—as gold and silver—in the process of roasting ores, especially such as contain tellurium, bismuth, antimony, sulfur, and other easily volatile substances.

My invention consists of a novel construction of combined muffle-furnace and condensing apparatus, which will be fully understood by the following description and claim.

25 The accompanying drawing represents a vertical section of my combined muffle-furnace and condensing apparatus.

In the construction of my new apparatus for roasting and retorting gold and silver ores 30 I make a furnace with a suitable outer wall, B, and place therein a muffle, A, which may rest on bars *a*, as seen in the drawing. This muffle is constructed so as to be closed air-tight, except an escape-pipe, E, through which 35 the fumes are to pass off into a large condensing-chamber, F, the operation of which will be hereinafter explained. The muffle has a door, C, provided with a small opening, *e*, for inspecting the ore in the process of roasting, 40 said opening being closed by a small slide, *b*. From the top of the muffle an escape-pipe, E, passes up through the outer wall of the furnace, and having a cock, *e*, extends to the condensing-chamber F, the capacity of which is 45 several times larger than the muffle, thus giving room for the gold and silver bearing fumes to circulate and cool without access of air or escape of the fumes.

The condensing-chamber F is to be closed 50 air-tight, and is provided with a removable top, G, having a clamping-bail, L, with thumb-

screw I and rubber packing *g*. This chamber also has a water-pipe, H, provided with a stop-cock, *h*, which is kept closed during the process of condensing the fumes and while the 55 fumes are yet escaping from the muffle. The condensing-chamber is placed lower than the furnace, so that the hot air and fumes, having once escaped from the muffle, more readily collect in the condensing-chamber without tendency to return to the muffle. 60

Operation: The muffle is charged with ore—say fifteen hundred pounds, more or less—and then the door C and slide *b* are closed and luted, when heat is applied. At the same time 65 the chamber F is closed air-tight by means of cover G and cock *h*, while the cock *e* is left open; also, a stratum of water—say four inches in depth—is put in the bottom of the condensing-chamber, in order to absorb the metallic 70 fumes, and thus collect the gold, silver, &c., escaping from the muffle. When no more fumes escape from the muffle (which is kept at cherry-red heat) the cock *e* is closed and the cock *a* opened, thus admitting a copious supply of water through pipe H to complete the 75 process of condensation. Now, the cover G may be removed and the surplus water drawn from chamber F by means of a siphon-tube, when the precipitated gold and silver will be 80 found collected at the bottom of chamber F. Afterward the ore in the furnace may be treated in the usual manner for obtaining the non-volatile metal or other products.

I am aware that it is not new to connect a 85 roasting-chamber and a condensing-chamber by means of a pipe provided with a stop-cock; but

What I claim, and desire to secure by Letters Patent, is—

The muffle A and pipe E, having the cock *e*, in combination with the condenser F, having cover G, clamp L, with water-supply pipe H, provided with cock *h*, all substantially as and for the purpose set forth.

In testimony whereof I affix my signature in presence of two witnesses.

MARTIN J. BUTZEL.
